UNITED STATES PATENT OFFICE.

JOSEPH THOMPSON LEONARD, OF ROLLING PRAIRIE, INDIANA, ASSIGNOR
OF ONE-HALF TO JOHN H. SHULTZ, OF EVANSTON, ILLINOIS.

DRAFTING INSTRUMENT.

SPECIFICATION forming part of Letters Patent No. 781,215, dated January 31, 1905.

Application filed June 25, 1904. Serial No. 214,203.

To all whom it may concern:

Be it known that I, JOSEPH THOMPSON LEONARD, a citizen of the United States, residing at Rolling Prairie, in the county of LaPorte and State of Indiana, have invented certain new and useful Improvements in Drafting Instruments; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to drafting instruments, and has for its object to provide a ruler especially designed for the projection of parallel and radial lines.

The principal object of my invention is to 20 provide a ruler adapted for the projection of parallel lines with great facility and a high degree of uniformity.

Another object of my invention is to provide a ruler adapted for the projection of lines 25 radiating from a common center and intercepting equivalent or predetermined arcs.

With these and other objects in view the present invention consists in the combination and arrangement of parts, as will be herein- 30 after more fully described, shown in the accompanying drawings, and particularly pointed out in the appended claims, it being understood that changes in the form, proportion, size, and minor details may be made within 35 the scope of the claims without departing from the spirit or sacrificing any of the advantages of my invention.

In the drawings, Figure 1 is a top plan view 40 of my improved ruler. Fig. 2 is a transverse sectional view on line 2 2 of Fig. 1. Fig. 3 is a transverse sectional view on line 3 3 of Fig. 1. Fig. 4 is a transverse sectional view on line 4 4 of Fig. 1.

Like characters of reference designate cor- 45 responding parts throughout the several views.

Upon either side of a main ruler-body 1 are disposed auxiliary straight-edges 2 and 3. These straight-edges are rigidly connected in

parallel relation to each other by transversely-disposed guides 4 and 5, which pass slidably 50 through the ruler-body 1. The transverse distance between the parallel members 2 and 3 is greater than the width of member 1, and the guides 4 and 5 are so mounted as to permit of an adjusting movement of members 2 and 3 55 in parallel relation with the member 1. Upstanding from the middle of guides 4 and 5 are pintles 6 and 7, preferably carrying thereon a cam-roller.

Above the guides 4 and 5 are mounted plates 60 8, capable of movement longitudinally along the member 1 and having formed therein diagonal cam-slots 9, disposed to embrace pintles 6 and 7.

Longitudinally upon member 1 is mounted 65 a shaft 10, journaled in bearings 11 and adapted for convenient rotation by means of the enlarged and milled portions 12. The shaft 10 is secured against longitudinal displacement by means of collars 13, rigidly mounted 70 thereon and abutting journaled bearings 11. The portions of shaft 10 which are disposed above the plates 8 are provided with oppositely-inclined screw-threads 14, adapted to engage screw-threaded members 15, rigidly 75 secured to plates 8.

Upon any convenient portion of the shaft 10, as upon the enlargement 12, is rigidly mounted a pin 16, adapted to contact at each revolution with a spring 17, secured to the 80 ruler-body 1.

A plate 18 is provided which is adapted to be secured above and to cover the plates 8 and screw-threaded members 14 and 15 to prevent interference with the accurate operation 85 thereof by any external object.

Within the ends of the ruler-body are disposed screws 19, adapted to be adjustably projected beyond the lower face of the ruler to raise the ruler to any desired height from the 90 work upon which it is being employed. The screws 19 are preferably so disposed within openings 20 as not to interfere with the free use of the ruler by projecting above the upper surface.

Upon one or both ends of the ruler is se- 95

cured a preferably circular plate 21, marked about its periphery in degrees. Above and bearing upon the plate 21 is disposed the wing 22, having a portion 23 conforming to the circular plate 21, with an indicator thereon properly placed to designate, in conjunction with the scale upon plate 21, the angle formed by the wing 22 with the ruler-body 1. The wing 22 is secured upon the plate 21 and against 10 rotary displacement by a thumb-screw 24, passing through the center of curvature of the portion 23 and engaging a screw-threaded opening in the center of plate 21. The wing 22 is provided with a curved portion or offset 15 25, adapted to permit the main wing portion 22 to bear against or adjacent to the work upon which it is being used.

The operation of my improved drafting instrument is as follows: With the parts disposed as shown in Fig. 1 the ruler is placed 20 so that the edge 3 will be in the position where the first of a series of parallel lines is required. The first line is now formed along the outer edge of member 3. The shaft 10 is then rotated by grasping enlarged portion 12 within 25 the fingers. The rotation of shaft 10 and the screw-threaded portion 14 will produce a longitudinal displacement of the member 15 and a movement of plates 8 toward each 30 other. The movement of the plates 8 and the cam-surfaces of slots 9 will cause a transverse movement of the pintles 6 and 7 and the guides 4 and 5 and the attached parallel straight-edges 2 and 3. At each revolution 35 of the shaft 10 the pin 16 will contact with the spring 17, thus indicating accurately when each revolution is completed. The straight-edge 3 being now moved a space nearer the ruler-body 1 is in position for the implace- 40 ment of the next parallel line, and the repetition of the operation will place the straight-edge in position for each successive parallel line. When through repeated operations the straight-edge 3 has been moved through the 45 full length of its course, the ruler may be reversed and the straight-edge 2 brought into use and the motion reversed, or the straight-edge 3 may be returned to the position shown in Fig. 1 by the reverse movement of shaft 50 10 and the entire operation repeated.

The wing 22 may be used for projecting successive radial lines intercepting equivalent arcs or for projecting lines at any desired angle to the main ruler-body by the loosening of the thumb-screw 24 and rotating the wing until the indicator on portion 23 indicates the required angle upon the scale-plate 21.

It is obvious that any number of pins 16 may be used, thereby permitting the projection of parallel lines with any desired amount of space intervening with absolute accuracy and great facility. It is further obvious that numerous other changes may be made without departing from the spirit of my invention.

Having thus described my invention, what 65 I claim as novel, and desire to secure by Letters Patent, is—

1. A ruler having auxiliary straight-edges disposed upon opposite sides thereof and parallel therewith, a rotatable shaft mounted longitudinally within the ruler-body, said straight-edges being connected for simultaneous transverse parallel adjustment, and means consisting 70 of the rotatable shaft.

2. A ruler having auxiliary straight-edges 75 disposed upon opposite sides thereof and parallel therewith, said straight-edges being capable of simultaneous transverse parallel adjustment and adapted to be shifted by a rotatable shaft disposed longitudinally within the 80 ruler.

3. A ruler having an auxiliary straight-edge parallel therewith and rigidly secured to right-angularly-disposed guides slidably mounted transversely within the ruler, and means consisting of a rotatable shaft mounted within the ruler adapted to slidably move said guides to adjust the straight-edge in parallel relation 85 to the ruler.

4. A ruler having auxiliary straight-edges 90 disposed upon opposite sides and parallel therewith and rigidly connected by right-angularly-disposed guides passing transversely through said ruler and means consisting of a rotatable shaft mounted within the ruler 95 adapted to slidably move said guides to adjust the straight-edges simultaneously in parallel relation to the ruler.

5. A ruler having an auxiliary straight-edge 100 disposed parallel therewith and rigidly secured to guides slidably mounted within the ruler and a shaft also disposed within the ruler and mounted for rotary movement to control the adjustment of the straight-edges in parallel relation to the ruler.

6. A ruler having auxiliary straight-edges 105 disposed upon opposite sides thereof and parallel therewith and rigidly connected by right-angularly-disposed guides passing transversely through the said ruler and a shaft disposed within the ruler and mounted for rotary movement to control the adjustment of the straight-edges in parallel relation to the ruler.

7. A ruler having an auxiliary straight-edge 110 disposed parallel therewith and rigidly secured to right-angularly-disposed guides 115 slidably mounted transversely within the ruler, pintles upstanding from the faces of said guides, plates with diagonal slots therein mounted upon said ruler adapted to embrace the pintles, and means for simultaneously and slidably moving the said plates longitudinally to impart a transverse parallel adjusting movement to the straight-edge.

8. A ruler having auxiliary straight-edges 120 125 disposed upon opposite sides thereof and parallel therewith and rigidly connected by guides passing slidably and transversely through the

said ruler, pintles upstanding from the face of said guides, plates with slots therein mounted upon said ruler and adapted to embrace the pintles, and means for simultaneously and slidably moving the said plates longitudinally to impart a transverse and simultaneous adjusting movement to the straight-edges.

9. A ruler having an auxiliary straight-edge disposed parallel therewith and rigidly secured to right-angularly-disposed guides slidably mounted transversely within the ruler, pintles upstanding from the faces of said guides, plates with diagonal slots therein mounted upon said ruler and adapted to embrace the pintles, a lug upstanding from said plate with a screw-threaded opening therein, a longitudinal shaft rotatably mounted, means for securing said shaft against longitudinal displacement, screw-threads formed upon said shaft adapted to engage the said lug and all so disposed that the rotation of the shaft simultaneously and slidably moves the said plates longitudinally to impart a transverse adjusting movement to the straight-edge.
10. In a ruler an auxiliary straight-edge disposed parallel therewith and capable of transverse parallel adjustment, a rod adapted to rotate and impart transverse motion to the straight-edge, a pin mounted upon the shaft and a spring member disposed to contact with said pin at each revolution of the shaft.

11. A ruler having an auxiliary straight-edge disposed parallel therewith and rigidly secured to right-angularly-disposed guides slidably mounted transversely within the ruler, pintles upstanding from the faces of said guides, plates with diagonal slots therein mounted upon said ruler and adapted to embrace the pintles, a lug upstanding from said plate with a screw-threaded opening therein, a longitudinal shaft rotatably mounted, means for securing said shaft against longitudinal displacement, screw-threads formed upon said shaft adapted to engage said lug and all so dis-

posed that the rotation of the shaft simultaneously and slidably moves the said plates longitudinally to impart a transverse adjusting movement to the straight-edge, a pin mounted upon the said shaft, and a spring member disposed to contact with said pin at each revolution of the shaft.

12. In a ruler the combination of a main ruler-body, an auxiliary straight-edge disposed parallel therewith, a rotatable shaft mounted within the ruler adapted to control a transverse parallel adjustment of the auxiliary straight-edge and an arm provided with a straight-edge pivoted at the end of the ruler-body and adapted for angular adjustment in relation to the ruler-body.

13. A ruler having an auxiliary straight-edge parallel therewith and rigidly secured to right-angularly-disposed guides slidably mounted transversely within the ruler and means consisting of a rotatable shaft mounted therein adapted to slidably move said guides to adjust the straight-edge in parallel relation to the ruler, and an arm with a straight-edge pivoted to the end of the ruler and adapted for angular adjustment in relation to the ruler.

14. A ruler having auxiliary straight-edges disposed upon opposite sides thereof and parallel therewith and rigidly connected by right-angularly-disposed guides passing transversely through the said ruler and a shaft disposed longitudinally within the ruler mounted for rotary movement to control the adjustment of the straight-edges in parallel relation to the ruler, and an arm with a straight-edge and pivoted to the end of the ruler adapted for angular adjustment in relation to the ruler.

In testimony whereof I affix my signature in presence of two witnesses.
